UNITED STATES PATENT OFFICE.

VERGIL MULHOLLAND, OF WEST HARTFORD, CONNECTICUT, ASSIGNOR TO HARTFORD-EMPIRE COMPANY, OF HARTFORD, CONNECTICUT, A CORPORATION OF DELAWARE.

APPARATUS FOR ANNEALING SHEET GLASS.

Application filed October 14, 1926. Serial No. 141,631.

This invention relates to apparatus for annealing sheet glass and it has particular relation to lehrs of the tunnel type, through which sheets or continuous strips of glass are transported by a conveyor, and in which they are subjected to varying temperature environments, in order to relieve stresses and strains that may exist in the glass.

One of the objects of this invention is to provide a lehr in which both the upper and the lower surfaces of the sheet glass will be subjected to a uniform temperature at any given cross sectional portion of the tunnel, and in which the temperature above and below the glass may be easily regulated throughout the entire length of the tunnel.

Briefly, this temperature control is obtained by providing a tunnel lehr having two separate and independent fire boxes, one above and one beneath the receiving end of the tunnel, and communicating respectively with heating flues extending longitudinally above and beneath the tunnel. The temperature in each of these flues is regulated at will by damper-controlled openings through which air from the outer atmosphere may be admitted into the flues in regulable quantities to dilute and cool the heated gases passing therethrough.

In the accompanying drawings:

Figure 1 is a diagrammatic longitudinal section through a tunnel lehr constructed in accordance with the invention;

Fig. 2 is a vertical transverse sectional view, on a larger scale, taken on line 2—2 of Fig. 1, and illustrating the method of connecting the flues to a common suction device;

Fig. 3 is a similar view taken on line 3—3 of Fig. 1 and illustrating the construction of the damper-controlled openings in the flues, and

Fig. 4 is a vertical longitudinal sectional view through a portion of the tunnel and illustrating the baffle plates for minimizing the draft above the glass.

Referring to the drawings, a relatively wide and low lehr tunnel 1 is illustrated as being constructed of a plurality of substantially similar metallic sections 2 arranged in end-to-end relation. The tunnel sections are mounted on rollers 3 which ride on rails 4 carried by a plurality of pedestals 5. By

means of this construction the tunnel is free to expand or contract with changes in temperature without warping or buckling. 55 Sheets of glass are transported through the tunnel by an endless conveyor 6, the ware-bearing strand of which traverses the tunnel and is supported therein through its length and breadth by the flat metallic bottom thereof. The idle strand of the conveyor 6 returns to the entrance end of the tunnel beneath the lehr and is supported by rollers 7. The conveyor 6 may be of any preferred construction and may be driven by any suitable 60 mechanism indicated at 8, Fig. 1.

Heating flues 9 and 10, respectively, extend longitudinally above and beneath the tunnel and respectively communicate, through damper controlled passageways 11 and 12, 70 with fire boxes 13 and 14 disposed one above and one beneath the receiving end of the lehr. A plurality of damper-controlled openings or stacks 15 and 16 are disposed at intervals longitudinally of the flues 9 and 10, respectively, and establish communication between these flues and the outer atmosphere. 75

Heated gases from the fire boxes 13 and 14 are drawn through the flues 9 and 10 by means of a common suction device 17, which communicates with the upper flue 9 through a damper-controlled passageway 18 and with the lower flue 10 through a damper-controlled passageway 19 and a pair of pipes 20 disposed one on each side of the tunnel. This 80 suction device may be of any preferred construction but is herein shown as comprising a motor-driven suction fan. Heat is prevented from dissipating too rapidly from the flues and from the tunnel by means of a suitable 85 casing 21 of insulating material. 90

By suitably adjusting the dampers in the passageways 11, 12, 18 and 19, the draft in the flues 9 and 10 may be regulated at will and by adjusting the dampers in the stacks 15 95 and 16, the amount of cooling air admitted into these flues may be regulated as desired in order to obtain the desired drop in temperature in the tunnel.

By reason of the fact that the sheet glass is 100 supported in proximity to the bottom of the tunnel as it passes therethrough, there is considerably more space above the glass than there is below. There consequently may be

a tendency for a current of air to flow through the tunnel above the glass and to disturb the desired heat conditions therein. While this difficulty may be partly compensated for by supplying more heat to the upper flues than to the lower, it may be found desirable to equip the tunnel with a plurality of transversely extending baffle plates or partitions 22, Fig. 4, which depend from the top of the 5 tunnel and are arranged at intervals therealong. These baffles are preferably cast integral with the top wall of the tunnel and extend downwardly to a point adjacent to the glass, sufficient clearance being provided to 10 prevent them from contacting with the glass when they expand under the influence of heat.

The draft above the glass is thereby reduced to that which may pass through the relatively small spaces between the upper 20 surface of the glass and the lower edges of the baffles 22. The air in the spaces between the baffles is in a substantially static condition and retains the temperature of the adjacent portions of the heating flue.

25 By means of the above-described construction, a uniform temperature may be readily maintained both above and beneath the sheet glass as it is transported through the tunnel, thus avoiding the difficulties hereinbefore encountered in lehrs which are heated only from below and in which the sheet glass forms an effective baffle or partition in the tunnel, which materially interferes with the circulation of the convection currents therein.

35 The illustrated embodiment of the invention may be modified in construction and arrangement without departing from the scope of the invention as defined in the appended claims.

40 I claim as my invention:—

1. Apparatus for annealing sheet glass, comprising a tunnel, means for transporting sheet glass therethrough, a heating flue extending longitudinally above said tunnel and 45 communicating with a fire box located above the receiving end thereof, a heating flue extending longitudinally beneath said tunnel and communicating with a fire box located beneath the receiving end thereof, and means 50 located at intervals longitudinally of each of said flues for controlling the temperatures in different zones of said tunnel.

55 2. Apparatus for annealing sheet glass, comprising a tunnel, means for transporting sheet glass therethrough, a heating flue extending longitudinally above said tunnel and communicating with a fire box located above the receiving end thereof, a heating flue extending longitudinally beneath said tunnel 60 and communicating with a fire box located beneath the receiving end thereof, and means located at intervals longitudinally of each of said flues for admitting atmospheric air into said flues to control the temperatures in 65 different zones of said tunnel.

3. Apparatus for annealing sheet glass, comprising a tunnel, means for transporting sheet glass therethrough, a heating flue extending longitudinally above said tunnel and communicating with a fire box located above 70 the receiving end thereof, a heating flue extending longitudinally beneath said tunnel and communicating with a fire box located beneath the receiving end thereof, and means located at intervals longitudinally of each 75 of said flues for admitting atmospheric air in regulable quantities into said flues to control the temperatures in different zones of said tunnel.

4. Apparatus for annealing sheet glass, 80 comprising a tunnel, means for transporting sheet glass therethrough, a heating flue extending longitudinally above said tunnel and communicating with a fire box located above the receiving end thereof, a heating flue extending longitudinally beneath said tunnel and communicating with a fire box located beneath the receiving end thereof, a single suction device communicating with both of 85 said flues for drawing heated gases from said fire box through said flues at subatmospheric pressure, and means located at intervals longitudinally of each of said flues for controlling the temperatures in different zones of 90 said tunnel. 95

5. Apparatus for annealing sheet glass, comprising a metallic tunnel, means for transporting sheet glass therethrough, a flue extending longitudinally above said tunnel, the top wall of said tunnel constituting the 100 bottom wall of said flue, a fire box disposed above the receiving end of said tunnel and communicating with said upper flue, a heating flue extending longitudinally beneath said tunnel, the bottom of said tunnel constituting the upper wall of said lower flue, a fire box located beneath the receiving end of said tunnel and communicating with said lower flue, means for causing the flow of heated gases through both of said flues at subatmospheric pressure, and a series of damper-controlled openings disposed at intervals longitudinally of each of said flues for admitting regulable quantities of air from the outer atmosphere into said flues to dilute and cool the hot gases passing therethrough and to thus independently control the temperatures in different zones longitudinally of said flues and tunnel. 110 115

6. Apparatus for annealing sheet glass comprising a tunnel, means for transporting sheet glass therethrough, similar longitudinal heating flues respectively above and below said tunnel, similar fireboxes communicating respectively with said flues at points opposite one another, and means to withdraw the heating media from said flues, whereby similar heat conditions may be maintained in the top and bottom of said tunnel. 120 125

7. Apparatus for annealing sheet glass 130

comprising a tunnel, means for transporting sheet glass therethrough, similar longitudinal heating flues respectively above and below said tunnel, similar fireboxes communicating respectively with said flues at points opposite one another, similar means for each flue spaced at intervals therealong for controlling the temperatures therein, whereby the heat conditions above and below the glass may be separately controlled, and means to withdraw the heating media from said flues. ¹⁰
Signed at Hartford, Conn., this 13th day of October, 1926.

VERGIL MULHOLLAND.
